CLAIM

We claim the ornamental design for a planter, as shown and described.

DESCRIPTION

FIG. 1 is a perspective view of a planter showing our new design in a state of use;

FIG. 2 is another perspective view of the planter showing our new design;

FIG. 3 is a front view of the planter of FIG. 2;

FIG. 4 is a rear view of the planter of FIG. 2;

FIG. 5 is a left side view of the planter of FIG. 2;

FIG. 6 is a right side view of the planter of FIG. 2;

FIG. 7 is a top side view of the planter of FIG. 2;

FIG. 8 is a bottom side view of the planter of FIG. 2;

FIG. 9 is a cross sectional view taken along line 9-9 in FIG. 7 showing the planter of FIG. 2;

FIG. 10 is another cross sectional view taken along line 10-10 in FIG. 7; and,

FIG. 11 is another cross sectional view taken along line 11-11 in FIG. 7.

The broken lines shown in FIGS. 1 and 3-11 represent portions of the planter and form no part of the claimed design. The dot-dash lines represent a boundary and form no part of the claimed design. The diagonal parallel lines in FIGS. 9-11 represent cross sectional view indicia and form no part of the claimed design.

1 Claim, 7 Drawing Sheets
